UNITED STATES PATENT OFFICE.

OTTO TROSSIN, OF HAMBURG, GERMANY, ASSIGNOR TO ERNEST MATTHIAS
ADALBERT FEUERHEERD, OF HAMBURG, GERMANY.

ROTATABLE GRATE.

No. 851,043.

Specification of Letters Patent.

Patented April 23, 1907.

Application filed February 2, 1907. Serial No. 355,443.

To all whom it may concern:

Be it known that I, OTTO TROSSIN, a subject of the German Emperor, and a resident of Hamburg, in the German Empire, have 5 invented a certain new and useful Improvement in Rotatable Grates, of which the following is a specification.

The present invention refers to a rotatable grate which is especially designed to be used 10 in furnaces for coal-dust and which can revolve about a horizontal axis.

The object is to make the working grating-surface properly adjustable as to its size and also to enable a regulation of the draft of air. 15 To this end the grate, which is made cylindrical, has one portion which has no openings, but is formed of a suitably-bent plate, which by rotating the grate can be moved away from the fireplace or more or less into 20 this place to replace the working grate proper.

In the drawings, Figure 1 shows a boiler-furnace in sectional elevation; and Fig. 2 shows the same in cross-section; the rotatable grating being shown to one-half in longitudinal section and to one-half in elevation. 25

The cylindrical grate A consists of two circular plates *a*, mounted on a horizontal shaft *d*, of a number of fire-bars *b*, and of a bent plate *c*, both fixed to the plates *a* by any 30 suitable means. Preferably the number of fire-bars encompass an angle of two hundred and forty degrees, so that the plate *c* fills up the remaining one hundred and twenty degrees.

35 The grate A contacts with the lower plate *f* of the door-frame in such manner that the vertical central plane of the grate is not far behind the back edge of this plate *f*. The shaft *d* is journaled in the walls of the furnace and may project out for a short distance to enable it to be turned. When it is 40 turned to the left, the plate *c* is brought

further into the fireplace B, and thus the working part of the grating proper is made smaller—that is, there is a smaller number 45 of fire-bars *b* lying in the space B. When the working grating is largest—that is, when the plate does not project into the space B at all—the feed of the air to the surface can be regulated alone by turning the grate A. 50

Evidently the grate may be used also for furnaces for other coal than for coal-dust.

I claim—

1. A grate comprising a plurality of fire-plates mounted to move in a circle and having supporting-faces at an angle to the radii of the circle and a curved plate movable with the bars concentric to the center of the circle. 55

2. A grate comprising supporting-disks, a plurality of flat fire-bars mounted therein having their faces at an angle to the radii of the disks, and a plate mounted in the disks concentric to the axis thereof. 60

3. A grate comprising a rotatable shaft, 65 parallel disks mounted thereon, a plurality of flat fire-bars mounted in the disks having their faces at an angle to the radii of the disks, and a curved plate secured to the disks concentric to the axis thereof. 70

4. In a furnace, the combination of a plate extending from the base of the door thereof into the fire-box, a rotatable shaft mounted in the latter, parallel disks mounted on the shaft, a curved plate mounted on the disks 75 adapted to intersect the plane of the aforesaid plate, and a plurality of flat bars mounted in the disks having their faces at an angle to the radii thereof.

OTTO TROSSIN.
